UNITED STATES PATENT OFFICE.

CHARLES EDGERTON, OF PHILADELPHIA, PENNSYLVANIA.

DIGESTER.

No. 899,961.

Specification of Letters Patent. Patented Sept. 29, 1908.

Application filed January 9, 1908. Serial No. 409,922.

To all whom it may concern:

Be it known that I, CHARLES EDGERTON, a citizen of the United States, and a resident of Philadelphia, in the county of Philadelphia 5 and State of Pennsylvania, have made certain new and useful Improvements in Digesters, of which the following is a specification.

My invention is in the nature of an improved digester to be used more particularly for cooking garbage through the agency of steam, for the recovery of the oils, fertilizer and other valuable constituents, but applicable to all uses in which steam may be employed for the purpose of promoting the separation of the liquid matters from solid matters or for subjecting semi-solid matters to the agency of steam.

It relates to that form of digester in which an outer containing vessel is provided internally with a rotating perforated receiver suspended within the outer container by means of trunnions, and provided with gears for rotation within the stationary container. In such digesters the discharge of the solid matters from the inner perforated receiver is attained with some difficulty either by reason of the construction of such perforated receiver or by reason of the construction of the outer containing vessel, and my invention consists in such construction of receiver and container as facilitates the discharge of both the solid and liquid matters, and which also provides a strong, braced construction which insures the coaxial alinement of the trunnion as hereinafter more fully described with reference to the drawing, in which—

Figure 1 is a vertical longitudinal section, and Fig. 2 an end elevation with the upper half in transverse section on line 2—2 of Fig. 1.

In the drawing the outer containing vessel and the inner perforated receiving vessel are made of substantially the same shape with parallel walls leaving an annular space between the same into which steam is introduced for the purpose of effecting the cooking of the garbage or other materials contained within the inner receiver. Both of these vessels are made substantially alike of five parts. The inner receiver consists of a relatively narrow cylindrical belt of sheet metal A, to the opposite sides of which are secured by rivets, two frusto-conical sections

A', A', and to the outer and smaller ends of which frusto-conical sections are similarly secured by rivets, the dished ends or heads A², A². In like manner the outer container consists of a narrow cylindrical belt B with two oppositely placed frusto-conical sections 60 B', B', and two dished heads B², B². The outer container is provided at suitable points in the frusto-conical sections with steam inlet and outlet pipes C, C, this outer container being constructed of boiler iron. 65 The inner receiver, which is of somewhat thinner material, is perforated throughout its middle portion with holes of a size suited to the character of the materials to be treated. These holes extend around the middle belt 70 A and may or may not extend throughout the parts A'.

The outer container is provided at coaxial points with hollow trunnions b b, whose flanges are bolted concentrically to the 75 dished heads B², B². Concentrically and coaxially within these hollow trunnions are arranged the journals a a having flanges which are bolted to the end heads A², A², of the receiver. Between the journals a of the 80 inner receiver and the hollow trunnions b of the container there are formed stuffing boxes provided with glands s to render the joint steamtight. The hollow trunnions of the outer container and the journals of the inner 85 receiver are mounted in bearings in the upper ends of standards D, D'. Fixed to the end of one of the journals a of the inner receiver there is a large gear wheel E⁴, which is in mesh with, and derives motion from, a small 90 pinion E³ mounted rigidly on a shaft E and having a step drive pulley E². The shaft E is journaled at one end in a bearing e' within the standard D' and at the other end is journaled in a bearing e in the separate shorter 95 standard D². Motion imparted to the shaft E and drive pulley E² causes, through the pinion E³ and large gear E⁴, a slow rotation of the perforated inner receiver within the stationary outer container.

At diametrically opposite points of the outer container in the middle cylindrical belt B are formed respectively the inlet and outlet openings. The inlet opening is formed by means of a cast collar B³ riveted to the 105 edges of the cylindrical belt and has a door b' with suitable fastenings for securing it tightly upon the collar. At the bottom of the

outer container there is attached a discharge coupling B^4 which may communicate with any suitable receptacle for receiving the solid and liquid matters after treatment. 5 At diametrically opposite points in the inner receiver there are also arranged inlet and outlet openings, closed respectively by sliding doors A^3 , A^4 . The door A^3 slides in curved guides a' , a' arranged transversely 10 on the periphery of the middle belt portion and the door A^4 slides in similar guides a^2 , a^2 , on the opposite side.

With the double frusto-conical construction of digester as thus described, it will be 15 seen that when the matters contained within the inner receiver have been sufficiently cooked by the steam jacket and the slow rotation imparted to said receiver through the gears, the contents of said receiver are 20 conveniently and easily discharged by their own gravity by simply opening the doors A^3 , A^4 , and rotating the inner cylinder. The mass of matter, being sustained upon the inclined sides of the lower surface of each end 25 of the receiver, gradually moves to the middle of the inner receiver and is discharged through the open doors A^3 , A^4 . In like manner the fluid matters pass down the inclined sides from each end of the outer container 30 and pass out through the outlet coupling B^4 . By this means also I am enabled to greatly strengthen the inner receiver, using only small outlet doors at A^3 , A^4 . With my constructions the double frusto-conical ends of 35 the receiver form a braced construction which preserves the coaxial alinement of both the journals of the inner receiver and the hollow trunnions of the outer container.

The outer container, or inclosing case, it 40 will be seen, is stationary and its mounting on the standards D D' is sufficiently high to hold the outlet B^4 in suspended position. This outlet coupling B^4 at the bottom of the apparatus is designed to connect with a 45 large gate valve which in turn is connected below to a receiving tank, the material dropping through under seal without the dissemination of odors to the external air,

which is a very important feature in treating certain materials.

50

I claim—

1. A digester comprising an outer stationary shell and an inner perforated and revolving receiver, both being formed with a cylindrical middle section and tapered end 55 sections decreasing in diameter from the middle and having one or more doors midway between the ends, and the outer container being formed at opposite points with inlet and outlet openings in alinement with the doors of the inner rotary receiver and elevated end supports for both vessels, the outlet of the outer container having a stationary pendent coupling adapted to make a sealed connection.

65

2. A digester comprising an outer containing shell and an inner receiver, both being formed alike with a relatively narrow middle cylindrical portion having inlet and outlet openings, opposite frusto-conical sections and dished end sections, the end sections being provided on their outer sides with coaxial trunnions elevated end supports for the same and means for rotating the inner container.

70

3. A digester comprising an outer container of double frusto-conical shape with diametrical openings in the middle and an inner receiver constructed of double frusto-conical shape, the middle portion of which 80 is formed with one or more outlets provided with curved and transverse guideways and curved sliding doors for the same.

75

4. A digester comprising an outer shell having a middle cylindrical portion and 85 double frusto-conical ends, an inner receiver also formed with a middle cylindrical portion and double frusto-conical ends, both being coaxially mounted on trunnions and provided with registering doors arranged 90 midway between the ends and elevated end supports for both vessels.

CHARLES EDGERTON.
